(57) **CLAIM**

The ornamental design for a digital camera body of lens
replacing type, as shown.

DESCRIPTION

FIG. 1 is a front, top and right side perspective view of a
digital camera body of lens replacing type showing my new
design;

FIG. 2 is a rear, top and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

1 Claim, 5 Drawing Sheets
